UNITED STATES PATENT OFFICE.

WILLIAM J. DUVALL, OF ST. LOUIS, MISSOURI, ASSIGNOR TO SMITH & DAVIS MFG. CO., OF ST. LOUIS, MISSOURI, A CORPORATION OF MISSOURI.

FOLDING BED.

Application filed February 7, 1924. Serial No. 691,309.

To all whom it may concern:

Be it known that I, WILLIAM J. DUVALL, a citizen of the United States, residing at St. Louis, and State of Missouri, have invented certain new and useful Improvements in Folding Beds, of which the following is a specification.

My invention has relation to improvements in folding beds, and consists in the 10 novel features of construction more fully set forth in the specification and pointed out in the claims.

The object of the present invention is to provide a bed having its head end mounted 15 on a rolling base and its bottom and foot end foldable against the head end so that the entire bed may be moved into a closet or other comparatively small enclosure when not in use. A further object is to provide a 20 folding bed in which the working mechanism at the head end is enclosed to preserve the appearance of the bed and at the same time to protect the mattress and covers. Further and other advantages will be better 25 apparent from a detailed description of the invention in connection with the accompanying drawings, in which—

Figure 1 is a top plan of the bed with part of the housing at the head end broken 30 away; Fig. 2 is a side elevation of the bed with the bed bottom shown in lowered position by full lines and in raised position by dotted lines; Fig. 3 is a vertical cross-section taken on the line 3—3 of Fig. 1; Fig. 4 is a vertical longitudinal section taken on the line 4—4 of Fig. 1; Fig. 5 is an enlarged 35 detail in perspective showing how the bed-bottom is hinged to the supporting frame at the head end of the bed.

Referring to the drawings, 1 represents the head frame of the bed provided with an inwardly extending base B consisting of a lower angle frame F and an upper angle frame F' connected by a pair of upright 40 angles 2, 2. The lower frame F is composed of an end angle bar 3 extending between the posts 4, 4 of the head frame and secured to the lower ends thereof, an end angle bar 5, and side angle bars 6, 6 connecting the 45 end angle bars 3 and 5. An angle bar 7 is carried by the side angle bars 6, 6 in slightly spaced relation with end angle bar 3 and an anchor weight 8 rests on and is secured to

the bars 3 and 7. The upper angle frame F' is composed of an end angle bar 9 secured between the posts 4, 4, at the height above their lower ends determined on for the plane of the bed-bottom, and a pair of side angle bars 10, 10 shorter than the angle bars 6, 6, the angle bars 10, 10 being secured to the ends of angle bar 9 and to the ends of uprights 2, 2. The upper angle frame F' will hereinafter be called the bed-bottom supporting frame because it carries the pivoted end of the bed-bottom as will more 50 fully appear. In order to stiffen the entire base B, corner braces 11, 11 are secured to the uprights 2, 2 and side bars 6, 6, and corner braces 12, 12 are secured to the posts 4, 4, and side bars 6, 6.

The bed-bottom comprises a pair of side rails 13, 13 connected at the foot end by an end rail 14, said side rails being pivotally mounted on a pivot pin p secured to the side angle bars 10, 10 of the supporting frame F' just outside of the uprights 2, 2, and the ends 13', 13' of the side rails at the head end are bent downwardly to come slightly below angle bar 9. An end rail 15 is secured to the downwardly bent ends 55 of the side rails 13, 13 and a plurality of tension springs 16, 16, etc., are secured to the end rail 15 and an angle bar 17 secured to the uprights 2, 2 slightly below their upper ends. When the bed-bottom is lowered there is tension on the springs 16 and since this tension is exerted on the end rail 15 which is below the pivot pin p the springs 16 create a tendency to raise the foot end of the bed which assists the operator in folding up the bed. Except for the ends 13', 13' of the side rails 13, said side rails lie in the 60 same horizontal plane (when the bed-bottom is lowered) as the angle bars 10, 10 hence these angle bars have their horizontal legs 10', 10' cut away at the ends to provide clearance for the side rails 13, 13. The major portion of each of the bent ends 13', 13' lies directly beneath the angle bars 10, 10.

A housing H entirely encloses the frames F and F' of the base B and has its top wall 17' secured to the angle bar 9 and inclined downwardly toward the front of the bed so as to just clear the springs 16 when the bed-bottom is lowered. To provide operat-

ing space for the ends 13' of the side rails, notches 18, 18 are cut into the sides at the front of said housing top wall 17.

A link fabric 19 is stretched over the bed-bottom, said fabric having its margins secured to the side rails 13 and end rail 14 by helical springs 20. However, at the head end of the bed the fabric is secured to the horizontal leg 10' of the angle bars 10 and 13 to the end angle bar 9. Thus at the head end of the bed the fabric extends over the housing top wall 17 and is spaced from it sufficiently so that the fabric will not touch this top wall under the weight of a person reclining on the bed. When the bed-bottom is folded to its upright position both the fabric 19 and mattress M will bend at about the pivotal point p. To keep the foot end of the mattress in place when the bed is folded up a pair of mattress clamps 21, 21 are provided on the end rail 14.

The foot end 22 of the bed is pivotally secured to the side rails 13, 13 by two pairs of links 23 and 24, and may be folded against 25 the bed-bottom when the latter is raised (Fig. 2 dotted).

Having described my invention, I claim:

1. A folding bed comprising a head end, a foot end, and a bed-bottom, said head end having an inwardly extending base comprising a lower frame and a bed-bottom supporting frame thereabove, a housing enclosing said frames at the sides and top

thereof, said bed-bottom having side rails and a head and a foot end rail, the side rails being pivotally mounted on said supporting frame a short distance from the head end rail, said side rails being on the same plane as the supporting frame from the foot end wall to the pivotal points and extending below this plane from the pivots to the head end rail, said head end rail extending below the top wall of the housing, means secured to the head end rail for counter-balancing the bed-bottom and a fabric stretched between the foot end rail and side rails up to the pivotal points, and stretched between the supporting frame members beyond the pivotal points.

2. A folding bed comprising a supporting base including a head frame and a bed-bottom pivotally mounted on said base, said base having a bed-bottom supporting frame and said bed-bottom having side rails mounted on said frame, the head ends of said side rails extending downwardly below the supporting frame, tension springs secured to said downwardly extending rail ends and the base, and a fabric secured to said side rails from the foot end of the bed-bottom to the side rail pivots, and said fabric being secured to said supporting frame between said pivots and the head frame.

In testimony whereof I hereunto affix my signature.

WILLIAM J. DUVALL.
